(57) **CLAIM**

The ornamental design for a dispensing applicator with a concave grip, as shown and described.

DESCRIPTION

FIG. 1 is a perspective view of the ornamental design for the dispensing applicator with a concave grip;

FIG. 2 is a second perspective view of the ornamental design for the dispensing applicator with a concave grip;

FIG. 3 is a left side view of the ornamental design for the dispensing applicator with a concave grip;

FIG. 4 is a right side view of the ornamental design for the dispensing applicator with a concave grip;

FIG. 5 is a top view of the ornamental design for the dispensing applicator with a concave grip;

FIG. 6 is a bottom view of the ornamental design for the dispensing applicator with a concave grip;

FIG. 7 is a front view of the ornamental design for the dispensing applicator with a concave grip; and,

FIG. 8 is a rear view of the ornamental design for the dispensing applicator with a concave grip.

Broken lines are shown for illustration purposes and form no part of the claimed design.

1 Claim, 4 Drawing Sheets
